UNITED STATES PATENT OFFICE.

JOSEPH D. GALLAGHER, OF GLEN RIDGE, NEW JERSEY, ASSIGNOR TO AMERICAN BRAKE SHOE & FOUNDRY COMPANY, OF MAHWAH, NEW JERSEY, A CORPORATION OF NEW JERSEY.

BRAKE-SHOE AND REINFORCING-BACK THEREFOR.

1,070,447.

Specification of Letters Patent. Patented Aug. 19, 1913.

Application filed March 24, 1913. Serial No. 756,307.

To all whom it may concern:

Be it known that I, JOSEPH D. GALLAGHER, a citizen of the United States, and a resident of Glen Ridge, in the county of Essex and State of New Jersey, have made and invented certain new and useful Improvements in Brake-Shoes and Reinforcing-Backs Therefor, of which the following is a specification.

- 10 My invention relates to brake shoes having a cast metal body, and a wrought metal reinforcing back embedded in the rear surface or back of the shoe, and to the wrought metal back itself, the object of the invention being to provide a construction in which the finished shoe, or rather the body portion thereof, is less liable to slip or crack longitudinally than is the case with shoes as now manufactured.
- 15 From my experience in the manufacture of brake shoes, I have found that there is often a tendency of the body portion of the shoe to break, crack or split longitudinally, particularly in those instances wherein the shoe is provided with inserts of cast or wrought metal, the result being that the shoe is liable to fall apart, or when held together, to so separate to cut or injure the tread of the wheel to which the shoe is applied.
- 20 The object of my invention is to cure this defect, and to so construct the shoe that there is little or no danger whatever of its cracking or splitting, and in the event that the shoe does so crack or split, to so hold or bind the parts or sections together that they will not start or separate to that extent wherein there is any danger or liability of the shoe cutting or injuring the tread of the wheel.
- 25 With this and other ends in view, my invention consists in the improved brake shoe, and reinforcing back therefor, hereinafter described and claimed, and illustrated in the drawing accompanying and forming a part 30 of this application, and in such variations and modifications thereof as will be obvious to those skilled in the art to which my invention relates.

In the drawing: Figure 1 is a view showing a sheet metal blank from which my improved reinforcing back is made; Fig. 2 is a view showing the completed back in perspective; Fig. 3 is a view showing my improved brake shoe in perspective; and Fig. 4 is a

view showing a section taken upon a transverse plane indicated by the line 4—4, Fig. 3.

Referring to the drawing, Fig. 1 shows a blank cut from a plate of steel or iron of a thickness of about $\frac{1}{16}$ ths of an inch, or thereabout, which blank comprises two substantially parallel sides or bars 6 connected with one another by a cross piece 7, and the ends of which sides are provided with projecting portions 8 extending toward one another. The sides 6 extend longitudinally of the finished shoe when embedded in the rear surface or back thereof, as shown in Fig. 3, and are curved to correspond with the curvature of the shoe during the bending processes to which the blank is subjected to produce the finished reinforcing back shown in Fig. 2.

The cross-piece 7 of the blank is bent to form an upwardly extending attaching lug 9 whereby the brake shoe may be secured to and supported from a brake head or similar support, as will be understood. This cross piece and the lug formed by bending the same is shown as integral with the sides 6, but the said cross bar may obviously be formed as a separate piece the ends of which are secured to the sides or bars of any form and in any way, or a previously formed lug may be secured in any way to bars such as the sides 6, to form a finished reinforcing back, as will be understood.

The combined length of the portions 8 adjacent the ends of the sides 6 is such that the extremities thereof extend past one another, or overlap as shown in the drawing, after the cross bar 7 of the blank has been bent to form the finished reinforcing back, the bending of the cross bar obviously resulting in bringing the sides closer to one another than was the case in the original blank. It is, however, immaterial whether these projecting portions are of the same length, or one longer than the other, so long as their ends extend past one another in the finished reinforcing back.

The reinforcing back formed as above explained is placed in a mold and the molten metal from which the body portion 10 of the shoe is formed is poured thereinto, whereby the back becomes embedded in the rear surface of the cast metal body of the shoe. The cast metal of the body of the shoe also serves as a means for locking the

free ends of the extending portions 8 together to thus prevent the ends of the sides 6 from spreading and the body of the shoe from splitting. The ends of these portions 5 should be formed or shaped in such a way that the cast metal of the body of the shoe may get a firm grip on them as the shoe is formed, this being accomplished in the embodiment of my invention illustrated, by 10 providing holes 11 adjacent the ends of the projecting portions 8, which holes register in the completed back, as shown in Fig. 2. It will then be obvious that as the body of the shoe is poured the fluid metal will flow 15 through the registering openings and thus lock the ends of the projecting portions together, thus, as will be understood from Fig. 4, preventing the body of the shoe from splitting or breaking along longitudinal planes or planes extending longitudinally of the body of the shoe.

Having thus described and explained my invention, I claim and desire to secure by Letters Patent:

25 1. A reinforcing back for a brake shoe comprising two sides, the free extreme ends of which are bent inwardly toward each other and provided with openings through which the cast metal of the body may flow, 30 and an attaching lug connecting said sides together.

2. A reinforcing back for brake shoes comprising two sides extending longitudinally of the shoe, the free end of each of 35 said sides being bent inwardly and provided with a hole therethrough, and an attaching key lug connecting said sides together about the center of the length thereof.

3. A reinforcing back for a brake shoe, 40 the same comprising two bars adapted to extend longitudinally of the body of the shoe and connected at about the center of their length with an attaching key lug, the free end of each of said sides being bent inwardly toward each other and overlapping, 45 each of said ends being provided with a hole therethrough to permit of the passage of the body metal into and through the same.

4. A reinforcing back for brake shoes 50 comprising two sides adapted to extend longitudinally of the shoe and the free ends of which sides are unconnected with one another; an attaching lug connecting said sides together; and means located at the ends of 55 said sides for locking said ends together.

5. A reinforcing back for brake shoes comprising two sides adapted to extend lon-

gitudinally of the shoe and the adjacent ends of which sides are provided with portions extending past one another and adapted to be engaged and locked together by the metal of the body portion of the shoe, and an attaching lug connecting said sides with one another.

6. A reinforcing back for brake shoes 65 comprising two substantially parallel sides adapted to extend longitudinally of the shoe and the adjacent ends of which sides are provided with portions extending past one another and having registering openings 70 through which the metal of the shoe may flow to thereby lock said ends together; and an attaching lug connecting said sides.

7. A brake shoe comprising a cast metal body portion; a reinforcing back embedded 75 in the rear surface of said body and comprising two substantially parallel sides extending longitudinally of the shoe and the adjacent ends of which sides are provided with portions extending past one another 80 and which portions are engaged and locked together by the metal of the body portions of the shoe; and an attaching lug connecting said sides with one another.

8. A brake shoe comprising a cast metal 85 body portion; a reinforcing back embedded in the rear surface of said body and comprising two substantially parallel sides extending longitudinally of the shoe and the adjacent ends of which sides are provided 90 with portions extending past one another and having registering openings through which the metal of the body of the shoe extends to thereby lock said ends together; and an attaching lug connecting said sides 95 with one another.

9. A brake shoe comprising a cast metal body portion; a reinforcing back embedded in the rear surface of said back and comprising a plurality of bars extending longitudinally of the shoe; connecting members whereby said bars are prevented from moving away from one another; and means whereby said connecting members and bars are locked together by the cast metal of the 100 body portion of the shoe.

Signed at New York, borough of Manhattan, in the county of New York and State of New York this 21st day of March, A. D. 1913.

JOSEPH D. GALLAGHER.
